MUSICAL TOY WHISTLE

Felis T. Segui, Gorman, Calif.

Filed Aug. 29, 1960, Ser. No. 63,412

Term of patent 3½ years

(Cl. D34—15)

I claim:

The ornamental design for a musical toy whistle, as shown and described.
